UNITED STATES PATENT OFFICE.

HOWARD M. DUDLEY, OF PHILADELPHIA, PENNSYLVANIA.

DYEING-MACHINE.

1,301,920.

Specification of Letters Patent. Patented Apr. 29, 1919.

Application filed February 2, 1918. Serial No. 215,054.

To all whom it may concern:

Be it known that I, HOWARD M. DUDLEY, a citizen of the United States, residing in the city of Philadelphia, county of Philadelphia, and State of Pennsylvania, have invented certain new and useful Improvements in Dyeing-Machines, of which the following is a full, clear, and exact specification.

My invention relates to fiber treating machines and refers particularly to devices suitable for the treatment of rolled fabrics with liquids.

The dyeing, bleaching and similar treatments of textile fabrics, are frequently accomplished by rolling or winding the fabric upon foraminous cylinders and forcing the liquid through the thus wound fabric.

In order to produce even and equal results in all parts of the fabric it is necessary that the flow of liquid be uniform through all portions thereof.

As the flow of the liquid through the fabric has a tendency to force the fabric outwardly of the roll, it is essential that the fabric be maintained in a uniform and constant state of compression during the operation.

In order to produce uniform results, it is also essential that all of the liquid be forced uniformly through the fabric roll, and special care must be exercised that this is accomplished along the edges of the roll, in order that the treatment at this part of the fiber may be the same as that of the interior portions.

The device of my invention accomplishes all of these objects and presents a simple, economical and effective method of producing uniform results throughout the entire fiber roll.

In order that the flow of liquid may be the same through all parts of the fabric, I close all openings in the foraminous cylinder except those portions covered by the fabric and in order to protect the edges of the roll, I cause an imperforate body to abut upon all portions thereof. My device also presents a means whereby the fiber roll is maintained under pressure and free from movement during the treating process.

As it is practically impossible to roll fabric so that the edges of the rolls will present an absolutely even surface, my device comprises a series of movable members which may be caused to abut upon the edge of the roll so as to overcome any inequalities therein and close all passages through which the liquid might pass other than through the entire fabric roll.

The means for closing a portion of the foraminous cylinder, for preventing the passage of liquid except through the entire roll and for maintaining the roll in a compressed condition during the treatment are clearly shown in the specification and by the drawings herewith which also disclose means whereby several rolls of fabric may be treated at the same time and under the same condition.

In the accompanying drawings illustrating modifications of my device, similar parts are designated by similar numerals.

Figure 1 is a broken vertical cross-section of one form of my device.

Fig. 2 is a view in the direction of the arrow 2 of Fig. 1.

Fig. 3 is a cross-section through the line 3—3 of Fig. 1.

Fig. 4 is an end view of a blade-holding means.

Fig. 5 is an end view of a fabric compressing means.

Fig. 6 is a side plan view of one of the blades with its accompanying parts.

Fig. 7 is a broken top plan development of a series of blades, with their holding means and fabric compressing means.

Fig. 8 is a vertical cross-section of two modifications of my device.

Fig. 9 is a view in the direction of the arrow 9 of Fig. 8.

Fig. 10 is a fragmental cross-section of a portion of my device.

The particular form of my device as illustrated in Figs. 1 to 7 inclusive, comprises a cylindrical member formed by the cylindrical side 20, a portion of which is foraminous 21, the imperforate end member 22 and the imperforate conical end member 23. The end member 23 is connected to a source of liquid 100

supply, not shown, whereby a liquid may be forced into the receptacle 24, within which is the imperforate member 25 for the purpose of more evenly distributing the liquid upon the inner face of the foraminous member 21. The cylindrical member carries the two integral flange members 26 and 27.

Capable of abutment upon the foraminous cylinder is a series of semi-circular members 28, 28^A; 29, 29^A; 30, 30^A; 31, 31^A, the two portions of each are hinged at 32 as shown in Fig. 2, and capable of being clamped together by the screw clamp 33. As these semi-circular members are similar, a description of but one will be given. Within the member 28 is a series of circular openings within each of which is a slidable bar 34, carrying a semi-circular member 35, a spring 36 abutting upon the members 28 and 35 causing the latter to have a normal outwardly position. The lower portion of the member 28 has a semi-circular extension 37, with a recess for the movement of the lower rod 34, and an inwardly extended semi-circular member 39 movable within a recess 40 within the lower member 35. The member 28^A has a corresponding series of members. When the members 28 and 28^A are clamped around the foraminous cylinder, the members 37, 37^A, 28, 28^A, 39, 39^A, 35, 35^A form a water tight abutment thereon. Between the members 26 and 28, 28^A is a series of toggles 41, each carrying an extended member 42 with a hole therein. Between the members 29, 29^A and 30, 30^A is a series of toggles 43, 43 each carrying an extended member 44 with a hole therein. Between the members 27 and 31, 31^A is a series of toggles 45, 45 each carrying an extended member 46 with a hole therein. Resilient rods 47, 47, 47 pass through holes in each series of members 42, 44, 46, the rods being connected by a series of turn-buckles 48, 48. The contraction of the rods 47, 47, 47 will thus force the members 28 and 29 toward each other and the members 30 and 31 toward each other, closing a portion of the openings in the foraminous cylinder. That portion of the foraminous cylinder between the members 29 and 30 is closed by means of the annular member 90 abutting thereon, the extended portions 91 and 92 of the members 29 and 30, respectively, being slidably movable thereover. A series of slots 93, 93 within the blades 50, 50, through which the pins 94, 94 pass allowing the blades 50, 50 to be moved inwardly or outwardly. In order to compress a fabric wound upon the cylinder, and to prevent its disarrangement during the forcing of a liquid through it, I use a series of blades 50, 50, each having a series of recesses 51, 51 and 52', 52'. Capable of placement across each recess 51 is a member 52 pivoted at 53 and fastened by the nut and

bolt 54. At each end of the blades 50, 50 is a series of rod projections 55, 55 capable of slidable movement within the recesses 56, 56 of the members 57, 57^A capable of placement upon the outer members 35, 35^A. The inner edge of each blade 50 is serrated 58, 58. A band 60, hinged at 61 and capable of being clamped at 62, has a series of recesses 63, 63 in which the blades 50, 50 may be fitted. When the blades 50, 50 are thus fitted into the recesses 63, 63, and the band 60 clamped, the inner edges of the blades 50, 50 will rest upon the fabric 100 wound upon the foraminous cylinder. In order to press the blades 50, 50 upon the fabric 100, a wire or rod 70, comprised of a series of sections attached together by means of the turn-buckles 71, 71 is placed within the recesses 52', 52', the turning of the turn-buckles 71, 71 pressing the blades 50, 50 inwardly. The foraminous portion of the cylinder comprises a series of spaced parallel bars 80, 80.

The operation of the device is as follows, assuming that the members 28, 28^A, 29, 29^A, 30, 30^A and 31, 31^A are abutting upon the foraminous cylinder:

90

Fabric 100 is wound upon the cylinder between the members 28 and 29 and between the members 30 and 31, and the members 60, 60, carrying the blades 50, 50 are placed in position upon the outer portion 95 of the fabric rolls. The turn-buckles 48, 48 of the wires 47, 47 are then turned thus pressing the members 35, 35, 35 against the sides of the wound fabric 100, through the medium of the toggles 41, 41. This movement also closes all of the openings of the foraminous cylinder except the portion upon which the fabric abuts. When sufficient pressure has thus been obtained, the turn-buckles 71, 71 are turned, thus forcing the 100 blades 50, 50 inwardly against the wound fabric. When a liquid is now forced through the chamber 24 of the cylinder, all of it will be forced outwardly and evenly through the wound fabric 100 thus treating 110 the edges of the fabric equally with the other portions thereof. The entire device, as shown, may be carried within a receptacle, not shown, for the receiving of the liquid and its return for future use, if desired.

115

In the modification shown in the left of Fig. 8, the member 28 of the form of the device previously described, is replaced by a series of stepped members 81, 82, 83 movable over each other and forming water-tight 120 abutments. The member 81 abuts upon the foraminous cylinder, and the members 82 and 83 have openings through which the members 84 and 85 of the toggles 41 may pass. The member 84 is integral with the 125 member 81, and the member 85 is integral with the member 82. The semi-circular member 35 of the first described form of my

device is replaced by a series of members 86, 86 slideable over each other and arranged in a series of semi-circles, the joints between the members 86, 86 being water-tight. Each 5 member 86 is pressed outwardly by a spring 36 abutting against the member 86 and a member 82, 83, 84. By this means the movement of the toggles 41, 41 causes each member 86, 86 to press firmly against the edge 10 of wound fabric upon the foraminous cylinder.

In the modification shown in the right of Fig. 8, the members 86, 86 have a flat exposed surface instead of a rounded one, as 15 shown in the left of that figure.

Fig. 10 shows a modified form of the members 86, 86 in which they are serrated on their exposed surface.

While I show my device operative with a 20 special form of foraminous cylinder, it is evident that it is applicable to other forms of such cylinders.

I do not limit myself to the particular size, shape, number or arrangement of parts 25 shown and described, all of which may be varied without going beyond the scope of my invention as described and claimed.

What I claim is:—

1. In a fabric treating device, in combination, a foraminous cylinder capable of having fabric wound thereon, a series of inner members abutting upon the foraminous cylinder, slideable thereon and capable of closing a portion of the openings therein, a 30 series of outer slideable members abutting upon the inner members and upon each other, toggle means for abutting the inner and outer members upon the edges of fabric wound upon the cylinder and for maintaining them in said abuttable position.

2. In a fabric treating device, in combination, a foraminous cylinder capable of having a series of rolls of fabric wound thereon, a series of inner members abutting 45 upon the foraminous cylinder, slideable thereon and capable of closing a portion of the openings therein, a series of outer slideable members abutting upon the inner members and upon each other, and means for slidably moving the inner and outer series 50 of members causing them to abut upon the edges of the series of rolls of fabric wound upon the cylinder.

3. In a fabric treating device, in combination, a foraminous cylinder capable of having a series of rolls of fabric wound thereon, a series of inner members abutting upon the foraminous cylinder, slideable thereon and capable of closing a portion of the openings 60 therein, a series of outer slideable members abutting upon the inner members and upon each other and toggle means for slidably moving the inner and outer series of members causing them to abut upon the edges

of the series of rolls of fabric wound upon the cylinder, maintaining them in said abuttable position.

4. In a fabric treating device, in combination, a foraminous cylinder capable of having a series of rolls of fabric wound thereon, 70 a series of inner members abutting upon the foraminous cylinder, slideable thereon and capable of closing a portion of the openings therein, a series of outer slideable members abutting upon the inner members and upon each other, means for slidably moving the inner and outer series of members causing them to abut upon the edges of the series of rolls of wound fabric and means for maintaining the wound fabric in an undisturbed 75 position during the forcing of a liquid therethrough.

5. In a fabric treating device, in combination, a foraminous cylinder capable of having a fabric wound thereon, an extended flange member integral with each end of the cylinder, a series of inner semi-circular members abuttable upon and slideable over the cylinder whereby the openings in the cylinder beneath the inner members are closed, 80 a series of abuttable, slideable members abutting upon the inner members and means for slidably moving the inner and outer members causing them to abut upon fabric wound upon the cylinder.

6. In a fabric treating device, in combination, a foraminous cylinder capable of having a fabric wound thereon, an extended flange member integral with each end of the cylinder, a series of inner semi-circular members abuttable upon and slideable over the cylinder whereby the openings in the cylinder beneath the inner members are closed, 90 a series of abuttable, slideable members abutting upon the inner members and means for slidably moving the inner and outer members causing them to abut upon fabric wound upon the cylinder.

7. In a fabric treating device, in combination, a foraminous cylinder capable of having a fabric wound thereon, an extended flange member integral with each end of the cylinder, a series of inner semi-circular members abuttable upon and slideable over the cylinder whereby the openings in the cylinder beneath the inner members are closed, 100 a series of abuttable, slideable members abutting upon the inner members and means for slidably moving the inner and outer members causing them to abut upon fabric wound upon the cylinder.

8. In a fabric treating device, in combination, a foraminous cylinder capable of having a fabric wound thereon, an extended flange member integral with each end of the

cylinder, a series of inner semi-circular members abuttable upon and slidable over the cylinder whereby the openings in the cylinder beneath the inner members are closed, 5 a series of abuttable, slidable members abutting upon the inner members, toggle means for abutting the series of members upon the edges of fabric wound upon the cylinder

maintaining them in said position and a series of movable blades capable of abutment upon the outer face of the wound fabric. 10

Signed at New York in the county of New York and State of New York this 24th day of January, 1918.

HOWARD M. DUDLEY.
